UNITED STATES PATENT OFFICE.

RALPH S. JENNINGS, OF BOSTON, MASSACHUSETTS.

LEATHER-STRETCHER.

SPECIFICATION forming part of Letters Patent No. 308,171, dated November 18, 1884.

Application filed September 19, 1883. Renewed April 23, 1884. (No model.)

To all whom it may concern:

Be it known that I, RALPH S. JENNINGS, a citizen of the United States, residing at Boston, in the county of Suffolk and State of Massachusetts, have invented certain new and useful Improvements in Leather-Stretchers, of which the following is a specification, reference being had therein to the accompanying drawings.

- 10 Figure 1 is a top plan view of the lower part of a stretching mechanism embodying my improvement. Fig. 2 is a longitudinal section through the whole mechanism, showing the upper and lower frames. Figs. 3 and 4 show 15 modified forms of certain parts. Fig. 5 is a longitudinal section of the leather and some of the stretching devices. Figs. 6 and 7 show a modification of the means for securing the frames together.
- 20 In the drawings, A A' represent the side pieces; A² A³, the end pieces of the frame, upon which the other parts of the mechanism are supported, and to which there may be legs A⁴ A⁴, if desired. Upon the frame thus produced there are arranged several rows of projections adapted to engage with one side of the leather and effecting a stretching thereof. I prefer to have them of the form shown—that is to say, they consist of round-surfaced projections situated in rows both transversely and longitudinally of the frame, the projections of each row being arranged at a distance apart substantially equal to the horizontal diameter of each projection; but these features may be varied more or less. I have found that if the projections be of the form of segments of spheres, they operate to the greatest advantage, as the pressure can be more uniformly distributed over the surface 35 of the leather than if they be of other shapes. These projections may be either formed integrally with supporting-bars B B, adapted to be secured to the frame, or they may be made separately from the bars and adapted to be 40 secured thereto; or the projections may be formed of wood, or may be cast in metal and secured to the wood, or cast in plates like that shown in Fig. 3, or cast with metal bars, like that in Fig. 4, and when made as in this

last-described method frames of various sizes 50 can be supplied.

D D' represent a movable platen, table, or frame, it also carrying projections constructed and arranged substantially similarly to those on the other frame. As shown in Fig. 55 2, the projections B² in this case are secured to the frame by means of bars E E. The projections B² are situated relatively to the path of travel of the movable frame in the same line with the recesses or open spaces between 60 the projections on the other frame, and when the movable frame is forced against the other the projections on the one will pass those on the other somewhat.

By examining the drawings it will be seen 65 that the projections on the frames can be so arranged as to form rows both transversely and longitudinally, the longitudinal rows corresponding with the recesses on the transverse rows, and as a result of this construction the 70 leather when being treated will be stretched not only on transverse lines, but also on longitudinal lines—that is to say, the slack or loose part will be taken out in both directions.

C represents a roller mounted across the 75 machine at one end. With it are combined devices for gripping the leather, which may be of the form of ordinary tenter-hooks, as at a'. At the other end of the frame there are similar hooks or fastening devices, a², which 80 may be, if desired, attached to a roller or attached to some stationary part of the machine. The slack produced in stretching the leather can be readily taken up by means of the roller or rollers, and with the latter are combined 85 ratchets or other devices for positively locking them, so that when they have been turned more or less they can be prevented from reTRACTING when the leather is under strain.

C' represents a roller by the side of the machine, to which one of the side edges of the leather is secured, the other side edge being suitably fastened either to the frame or to another roller. By means of these rollers the transverse slack or looseness can be taken up 90 and the leather kept taut. The movable platen or frame can be carried to and from the other in any suitable way.

I have shown in the drawings devices by means of which great power can be exerted, and which at the same time will permit the movement of the parts to be delicately adjusted.

5 F are screw-rods, there being in the construction shown in Figs. 1 and 2 one of these at each corner of the table, though it will be readily seen that a single screw or more could be used in any of the well-known ways to accomplish the purpose. As shown, each is mounted on the lower frame in a sleeve, F', and each engages with a nut, F'', on the movable frame or platen, and when the screws are rotated the platen will be carried up or down.

Any well-known mechanism can be used to cause a simultaneous rotation of all the screw-rods. That shown consists of a series of beveled wheels, h, on the screw-rods, beveled wheels h', carried by cross-shafts, and beveled wheels i, carried by a side shaft, I. When the crank I' on the latter shaft is turned in one direction, the platen will be carried up, and when turned in the opposite direction, down.

25 In Figs. 6 and 7 I have shown a form of the stretcher especially adapted to permit a large number of hides to be stowed away in a drying-room or other place. The frames are here forced together by means of levers, which can be fastened in any preferred way after the desired tension has been reached; or, instead of either of the methods and devices above shown for the purpose of bringing frames together, the gravity of the upper one may be depended upon, or its gravity may be supplemented by the weight of additional material placed thereon for the purpose of forcing it down after the leather is in place. While the leather is held stationary it is forced into such position 35 that in longitudinal section there is given a sinuous or undulating line, as shown in Fig. 5, the leather at this time being held stationary and the sinuous or undulating line extending from substantially one end of the 40 leather to the other. It will be also seen that when the projections are made in the manner described, if a section be taken through a row of the projections transversely of the machine, the leather will describe a line which is sinuous or wavy.

50 As the leather is pressed in the manner above described over the projections there are formed in it cup-shaped cavities or depressions, in forming the walls of which the slack is taken out of the leather in both directions.

55 It will be seen that the invention relates to an improvement in the art of stretching leather consisting in applying pressure upon opposite sides of the same in both a longitudinal direction and in a transverse direction while the leather is under tension—that is to say, while that portion of it which is being stretched is prevented from being pulled or drawn bodily relatively to the stretching devices. The preventing of such a bodily movement may be 60 effected by any well-known device adapted

to such a purpose. I have shown ratchet wheels and pawls combined with rollers to accomplish this result, and have arranged them outside of the two sets of projections 70 and open spaces; but it will be readily seen that for these could be substituted other means for preventing the leather from moving bodily while the sets of projections of howsoever great a number are effecting the stretching. 75

What I claim is—

1. The herein-described improvement in the art of stretching leather while under tension, which consists in applying pressure upon opposite sides of the same in both a longitudinal direction and in a transverse direction, whereby the slack or looseness of the fibers of the leather is taken up in both of said directions at once, substantially as set forth. 85

2. The improvement in the art of stretching leather while under tension, which consists in applying pressure upon opposite sides of the same in both a longitudinal and a transverse direction, then relieving it of such pressure 90 and taking up the slack by applying further tension, substantially as set forth.

3. In a leather-stretcher, the combination of a frame with projections arranged to form both several transverse series, those of each 95 series being isolated from each other by intervening recesses, and also several longitudinal series of projections, each series of these longitudinal projections being on the longitudinal line of one of the aforesaid series of 100 recesses, an opposing frame with corresponding projections and recesses, the projections on one side of the leather being opposite to the recesses on the other side, and vice versa, substantially as set forth. 105

4. In a mechanism for stretching leather, the combination of the frame on one side of the leather, a series of projections on said frame, the frame on the other side of the leather, a series of projections thereon alternating with those on the first aforesaid frame, and means for forcing said frames toward each other, whereby the leather is caused to take substantially the position shown—that is to say, such position that a section through it 110 gives a wavy or sinuous line from substantially one end to the other, as set forth.

5. The combination of the supporting devices upon one side of the leather arranged to form supports for the leather on lines transverse thereto with intervening spaces on transverse lines and to form longitudinal supports with intervening longitudinal lines of open spaces, means for forcing the leather down into the said open spaces, devices at one end 120 of the series of supports for holding the leather stationary, and devices at the other end of the series of supports for holding it also stationary there, substantially as set forth. 125

6. The combination of the supporting devices upon one side of the leather arranged, substantially as set forth, to provide open

spaces between the supports into which the leather can be pressed, a frame upon the other side of the leather, projections carried thereby and adapted, substantially as set forth, to
5 press the leather into said open spaces, the means which prevent the leather from moving bodily, and a lever adapted, substantially as described, to cause an approaching of the said

projections to or into the said open spaces, substantially as set forth. 10

In testimony whereof I affix my signature in presence of two witnesses.

RALPH S. JENNINGS.
